PAGE-FORM TIE-UP

Clifford F. Hanlen, Phoenix, Ariz.

Application July 18, 1936, Serial No. 91,280

2 Claims. (Cl. 101—404)

My invention relates to devices for temporarily holding together, or tying up, page forms of "linotype", to keep the same intact after the first set-up and after the removal of the chase, and to hold the same together on the chase truck or in storage trays. It is particularly efficient for use in connection with my elevating form file, Patent Number 1,682,078. In connection with this device my page-form tie-up may be placed about the page-form immediately after the removal of the chase and while it is resting on the truck. The truck may then be moved to the elevating form file and the entire page-form slid directly on to one of the receiving trays in said elevating form file. This invention is to be distinguished from type clamps and page fasteners used on page forms of individual type, since they necessarily clamp the ends as well as the edges of the form, whereas my device, being adapted for "linotype", clamps only the sides, and this permits of an efficiency and simplicity of construction not heretofore attained.

The objects of my invention are, first, to provide a tie-up to hold page-forms of "linotype" together temporarily which is easily and cheaply manufactured and which may be easily and quickly placed around and detached from page-forms of "linotype"; second, to provide such a device wherein side plates adapted to press against the sides of the "linotype" page-form may be resiliently held together to hold the form intact; third, to provide such a device wherein said side plates are adjustable in length; fourth, to provide such a device wherein the side plates being adjustable in length may resiliently resist extension whereby a slight compression will be afforded the end elements of my tie-up to assist in keeping the columns longitudinally in place; fifth, to provide a page-form tie-up which may be placed over the "linotype" page-form, after the removal of the chase, by the single manual operation of one person; and sixth, to provide a page-form tie-up which, when not in use, may be stored in a minimum of space. Other objects will appear hereinafter.

I attain these objects by means of the devices illustrated in the accompanying drawing, in which—

Fig. 1 is a perspective view of the top of a chase truck with the page-form tie-up shown thereon and in place, surrounding a page-form of "linotype"; Fig. 2 is an enlarged view of the page-form tie-up as it appears when not in use and removed from the page-form; and Fig. 3, a section of one of the side elements of the page-

form taken on line 3—3, Fig. 2. Similar numerals refer to similar parts in all views.

My page-form tie-up consists, essentially, of two side bars or lateral elements 2 and 3, joined together at their respective top and bottom ends, by two long, normally closed, springs or end elements 4 and 5. In its simplest form, the side bars may be of solid construction and cut so that their length is equal to the page-form on which they are to be used.

The end elements or springs 4 and 5 are of a length so that in normal condition, fully compressed, they are approximately two-thirds of the width of the page-form upon which they are to be used. The material of which they are made, and the size of the spiral, is such that when expanded to the width of the page-form they each exert about three pounds compressive pull. Loops or hooks are made at each end of these springs, by bending the spring coils at right angles, and these attach to lugs 6 in the ends of the side bars.

Since the page-forms are not always of uniform length, in the preferred form of my tie-up, I provide side bars of adjustable length. In the form herewith illustrated, this adjustment is made possible by a double tongue and groove arrangement between two elements of the complete bar. Thus, the left hand part or element 10 of the bars is of solid metal, provided with longitudinal notches 7 extending along the inner top and bottom edges of its inner portion. The right hand part 11 of this bar consists of a length of lighter weight sheet metal folded at its edges so that they extend around and over the edges of the left hand portion of the bar and into the grooves 7. The metal of this portion of the bar is of such thickness that it fits flush into the notches 7 on the inner side 12 of each left hand portion of the side bars. This construction makes it possible for the bar to present a smooth face 12 to the sides of the page-form.

The folds of the edges of the right hand portion 11 of side bar 2, it will be noted, form top and bottom channel ways to slideably receive the notched edges of the left hand portion 10 of the bar.

In order to provide a tension tending to normally contract two portions of the side bars, thus forming a resilient resistance against extension thereof, the spring 9 is attached between the extreme right hand end of the portion 10 and the left hand end of the bar portion 11, the ends of the spring being attached at 15 and 16 to the respective parts. This is a long coiled closed

spring and is of a diameter so that it fits within the groove or recess between the upper and lower channel or folded part 11 and does not extend beyond the inner face 12.

5 Side bar 3 is of identical construction as side bar 2.

The tie-up is assembled with the inner faces 12 of each side bar facing inwardly, so that the smooth sides will be presented to the edges of 10 the "linotype" of the page-form.

Heretofore, it has been necessary to tie the page-forms together with string or tape and two or three men were necessary to slide the form thus tied together from the top of the chase 15 truck to the storage tray. Two men were necessary to hold the tray and one to slide the form, in order to keep it intact.

In the operation of my page-form tie-up only one operator is necessary. After the removal of 20 the chase from the page-form, my tie-up is placed therearound as follows:—

In Fig. 1 page-form 18 is shown resting on the top of chase truck 19. The furthermost bar 3 is extended until it is of a length equal to the 25 side of the page-form furthest from the operator. This bar is placed with its inner face against the edges of the "linotype" on this further side of the page-form. The operator then 30 expands the nearer bar 2 to the same length and, grasping this latter bar at each end, expands the end element springs 4 and 5 until side bar 2 may be placed with its inner face against the nearer 35 side of the page-form. Each side bar may then be longitudinally compressed until it is the proper length and so that there is a slight tension on the end elements 4 and 5 against the ends of the "linotype" columns. The page-form may then be slid sideways, as indicated by arrow 40 26, onto any storage tray or shelf. Removal of the tie-up is very simple, since it is only necessary to lift one side element away from the form and thence move it upward until it clears the top 45 of the type. In this position the tension of the side element may be released, and the opposite side element may be removed clear of the form.

Heretofore, there have been devices made and

patented of a somewhat similar nature. These were, however, designed for use on page-forms of individual type and were designed and made to provide take-up and compression faces both lateral and longitudinal on the page-form of type. 5 While it is conceivable that some of these devices might be adapted for use on "linotype", their operation would nevertheless, be inefficient, since it is necessary to expand them both laterally and longitudinally in placing them over the 10 page-form. This operation would, necessarily, require two men, one to hold the form expanded in one direction while the other expanded it in the opposite direction to fit over the form.

Having now fully described my invention, its 15 use and operation,

I claim:

1. A page-form tie-up for "linotype" page-forms, comprising composite side bars, slideably adjustable as to length, composed of a left hand 20 portion having longitudinal notches along its upper and lower edges, a right hand portion having folded upper and lower edges to provide channelways to receive the notched edges of said left hand portion whereby a smooth inner face is provided, and a long coil spring attached intermediate said bar portions, to provide a tension tending to resist lengthening of said bar, in combination with end elements composed of two long coil springs attached respectively to lugs on the 25 adjacent ends of said side bars.

2. A page-form tie-up for "linotype" page-forms, comprising composite side bars, slideably adjustable as to length, composed of one portion having longitudinal notches along its upper and 30 lower edges, and a second portion having folded upper and lower edges providing channel ways to receive the notched edges of said first portion, thereby to provide a smooth inner face for said side bar, and resilient means intermediate said 35 bar portions normally tending to resist lengthening of said bar, in combination with end elements comprising resilient means of attachment intermediate the adjacent ends of said side bars.
